MATERIAL PRESSER FOR SEWING MACHINES

Emil Siefermann, Karlsruhe-Durlach, Germany,
assignor to Gritzner-Kayser A.-G., Karlsruhe-
Durlach, Germany, a corporation of Germany

Application October 4, 1938, Serial No. 233,304
In Germany October 5, 1937

4 Claims. (Cl. 112—60)

My invention relates to a material presser for sewing machines, more particularly machines for sewing leather.

In leather sewing machines, it is known to provide material pressing devices which press upon the workpiece by means of spring action which can be locked in that position and which can be released during the feeding of the workpiece by means of a ratchet wheel drive.

10 However, the known devices have many disadvantages and it is an object of my invention to provide an improved material presser for sewing machines.

15 A further object of the invention is to provide a simplified drive for such a presser.

A still further object of the invention is to provide a drive for a material presser which includes a direct connection between the material presser lever and the operating means therefor.

20 It consists in that with the material presser lever, a rack and pinion wheel is directly connected, which wheel contacts a toothed wheel, the latter being connected with the ratchet wheel which is pawl driven.

25 The invention further includes an especially simple construction of the device for lifting the ratchet pawl from the ratchet wheel. It is a rotary disk connected with a ratchet wheel and having a swinging lever carrying the ratchet 30 pawl, mounted tangentially to this disk in such manner that said lever at the end of the stroke is pushed out of the locking position by said disk against spring action.

With the foregoing and other objects in view, 35 the invention consists in the details of construction and in the arrangement and combination of parts to be hereinafter more fully set forth and claimed.

In describing the invention in detail, reference 40 will be had to the accompanying drawing forming part of this application, wherein like characters denote corresponding parts in the several views, and in which—

Figure 1 is a section of line I—I of Fig. 2; and 45 Figure 2 is a plan view.

In the frame 1 of the leather sewing machine, a material presser 3 is fixedly mounted on a shaft 2. The shaft 2 has fixedly mounted thereon a lever 4. The material presser 3 is pressed into 50 engagement with the workpiece 6 by means of a spring 5. This may be accomplished by the pushing of the upper end of the spring 5 against the shoulder 30 of a member 31 which is pivotally connected, as at 32, with the lever 4 between 55 the free end thereof and the shaft 2. A portion

33 of the member 31 engages the upper end of the spring to retain the same in operative engagement. The other end of the spring 5 rests in a tube 34 closed at its lower end 35 and hung up by means of a flange 36 at its upper end in a hole of a bottom wall 37 of the frame 1. Obviously, other connections between the spring 5 and lever 4 could be used without departure from the spirit and scope of the invention. In this position, the lever 4 and presser 3 can be locked by means of any suitable device such as a wedge 49 forming a movable extension of lever 4, which wedge is pressed to the left by means of a spring 49^a. An eccentric disc 49^b is mounted on a shaft 13^a, which disc rests against the lower surface of the wedge 49, thus supporting it. Shaft 13^a with the eccentric disc 49^b is turned and adjusted by a hand wheel 7 which is mounted on the shaft 13^a. Wedge 49 carries at its left end a roller 49^c for a purpose to be described later. In the upper part of the arm 4 there is formed a slot 50 which is partially covered by a plate 51 slidably resting on the arm 4 and connected to the member 49 by screws 52.

20 In the frame 1, a drive crank shaft 9 rotates in bearings 8. This shaft is driven by the handle 42 of a disc flywheel 41 by means of toothed wheels 40. The crank 9 of the shaft 9 drives a rod 43 (shown broken off) which actuates the needle holder with needle (not shown). Furthermore the shaft 9 carries a disk 44 for driving the thread take-up (not shown).

25 A lever 11 is fixedly connected to the inner end of a pin 45 which is rotatably mounted in a bearing 46 of the frame. The other end of the pin 45 rigidly mounts a lever 47. This lever 47 is actuated in any suitable manner (not shown) by the hand wheel 7 to turn the pin 45 in its bearing 46. The upper end 11^a of the lever 11 fixedly mounts a plate 48 which is in engagement with the roller 49^c of wedge 49 slidably mounted in the lever 4 and forming part of the locking device for the lever 4 and the presser 3. The wedge 49 is subjected to the action of the spring 49^a as aforesaid which presses it to the left against the edge of the plate 48 into the locking position. It is obvious from the foregoing that if by means of the hand wheel 7 the pin 45 is rotated in a clockwise direction (Fig. 1), the upper end 11^a of the lever 11 with the plate 48 and the wedge 49 will be pushed to the right, thereby unlocking the lever 4 and the presser 3. A reverse rotation of the pin 45 again locks the lever 4 and the presser 3.

30 An arm 11^b of the lever 11 has a roller 11^c 40

45

50

55

mounted thereon which is in engagement with the periphery of a disk 10 fixed on the shaft 9. The disk provides a cam 10^a which, as shaft 9 rotates periodically engages the roller 11^c, there-
5 by raising the arm 11^b and pushing the end 11^a of the lever 11 with the plate 48 to the right and unlocking the lever 4 and presser 3 by pushing the wedge 49 to the right. Thus, aside from the hand unlocking of the lever 4, the latter is peri-
10 odically unlocked and locked automatically as the shaft 9 rotates.

The material presser lever 4 rigidly mounts an angular extension 12 on which a rack 12^a is formed which contacts a pinion wheel 13 on the shaft 13^a. Also mounted on shaft 13^a is a ratchet wheel 14 and a circular disk 15, the latter being of larger diameter than the ratchet wheel. By means of a spring 16, the ratchet wheel 14 and with it the pinion 13 is pulled in a position corre-
15 sponding to the locked position of the material presser 3.

A pawl 17 serves to move the ratchet wheel 14, said pawl being carried by a ratchet pawl lever 18. This lever 18 is swingingly mounted on an arm 19^a of a mitre lever 19 mounted on the machine frame and is actuated in a direction to engage pawl 17 with ratchet 14 by a tension spring 20, connecting the free end of lever 18 to another arm 19^b of lever 19. The spring 20 steadily draws 25 pawl 17 in the direction of its contact with the ratchet wheel 14. The mitre lever 19 is actuated by means of a cam disk 21 mounted on the crank shaft 9. One arm 19^b of said lever mounts a roller 19^c which is drawn against this disc-like 30 cam 21 by means of a spring 22 connected to an additional lever arm 19^d. The ratchet pawl lever 18 lies in the same vertical plane as the circular disk 15 and about tangential to it, while the pawl 17 lies in the vertical plane of ratchet wheel 14.

40 When the material presser 3 is locked in the pressing position, the cam disks 10 and 21, together with levers 18 and 19 assume the position indicated in dotted lines in Fig. 1. In this position, the pawl 17 contacts the ratchet wheel 45 14 at the beginning of the ratchet stroke thereof. After the completion of the sewing stitch, after the needle (not shown), has left the workpiece 6, the mitre lever 19 is pressed to the right, as indicated by solid lines as the roller 19^c is engaged 50 by the cam 21 which rotates in the direction of the arrow 23. This lowers ratchet pawl lever 18 with pawl 17 and turns the ratchet wheel 14 in a counter-clockwise direction. In consequence, rack 12 is lowered by means of the pinion wheel 55 13 which depresses arm 4 and lifts the material presser 3. In its movement to the right and downward, the ratchet pawl lever 18 steadily approaches the circular disk 15 until it engages the latter. In the succeeding movement, lever 18 is 60 held against further movement to the right by the circular disk 15, until continued downward movement of the pawl 17 causes it to disengage from the teeth of the ratchet wheel 14. This completes the stroke of the ratchet wheel. The 65 spring 5 again presses the material presser 3 onto the workpiece 6 and thereby turns back toothed wheel 13 and the ratchet wheel 14. This turning back movement is aided by spring 16. The ratchet pawl lever 18 with pawl 17 and the mitre 70 lever 19 carrying it return also during this movement to the starting position, in which the pawl 17 again contacts the ratchet wheel 14. Meanwhile, of course, cam 10^a of disc 10 has raised arm 11^b to unlock arm 4 as previously described.

75 It is obvious that changes can be made in the

above described device so it is not my intention to limit myself to the precise embodiment shown, except as hereinafter claimed.

Having thus described my invention, I claim:

1. In a sewing machine of the class described, 5 a material presser for releasably holding the work to be sewed in position for sewing, a shaft mounting said presser for arcuate movement into and out of engagement with said work, an arm fixed on said shaft, an angular extension of said arm, 10 a rack formed on said extension, a pinion engaging said rack, a shaft fixedly mounting said pinion, a ratchet wheel fixed on said shaft, a ratchet wheel spring connected to said ratchet wheel and normally urging the same in one direction, 15 a disk fixed on said shaft adjacent said ratchet wheel, said disk having a slightly greater diameter than said ratchet wheel, said second shaft, pinion and rack comprising means for moving said presser into and out of engagement with the work, a drive shaft, a cam fixed on the same, a spring loaded lever engaging said cam and oscillated thereby, a pawl carried by said lever, said pawl engaging said ratchet wheel for a limited period during each oscillation of said 20 lever to rotate said wheel a predetermined distance against the action of said ratchet wheel spring.

2. In a sewing machine of the class described, 30 a material presser for releasably holding the work to be sewed in position for sewing, a shaft mounting said presser for arcuate movement into and out of engagement with said work, an arm fixed on said shaft, an angular extension of said arm, a rack formed on said extension, a pinion engaging said rack, a shaft fixedly mounting said pinion, a ratchet wheel fixed on said shaft, a ratchet wheel spring connected to said ratchet wheel and normally urging the same in one direction, 35 a disk fixed on said shaft adjacent said ratchet wheel, said disk having a slightly greater diameter than said ratchet wheel, said second shaft, pinion and rack comprising means for moving said presser into and out of engagement with the work, a drive shaft, a cam fixed on the same, a spring loaded lever engaging said cam and oscillated thereby, a pawl carried by said lever, said pawl engaging said ratchet wheel for a limited period during each oscillation of said 40 lever to rotate said wheel a predetermined distance against the action of said ratchet wheel spring, a second cam on said drive shaft, a second oscillating lever actuated thereby, and means associated with said second lever for locking said 45 presser in a work holding position.

3. In a sewing machine of the class described, 50 a work engaging member, a ratchet wheel, an operative connection between said wheel and said member whereby rotation of said wheel in one direction moves said member out of engagement with said work and vice versa, a spring loading said wheel against rotation in a work disengaging direction, and means periodically engaging said wheel and movable to rotate the same in a work releasing direction, and a camming 55 mechanism continuously driven and operative to periodically release the engagement of the wheel engaging means whereby to permit said spring to rotate said wheel and reengage said work.

4. In a sewing machine of the class described, 70 a work engaging member, a ratchet wheel, an operative connection between said wheel and said member whereby rotation of said wheel in one direction moves said member out of engagement with said work and vice versa, a spring loading 75

said wheel against rotation in a work disengaging direction, a pawl periodically engaging said wheel and movable to rotate the same in a work releasing direction, means periodically releasing the engagement of said pawl with said wheel to permit said spring to rotate said wheel to re-

engage said work, said last named means including a camming mechanism continuously driven and having operative connection with the pawl to move the latter into and out of engagement with said ratchet wheel.

EMIL SIEFERMANN.
